Primary Examiner—Ralf T. Seifert**[57]****CLAIM**

The ornamental design for the nonslip tip for walking aid, as shown and described.

DESCRIPTION

FIG. 1 is a front elevational view of the nonslip tip for walking aid showing my new design;

FIG. 2 is a rear elevational view showing a use thereof;

FIG. 3 is a left side elevational view thereof;

FIG. 4 is a right side elevational view thereof;

FIG. 5 is a top plan view thereof; and,

FIG. 6 is a bottom plan view thereof.

The wavy lines on an end portion of the top circumferential strap in FIGS. 1, 3, and 5 represents hook or loop fastener material.

The broken line showing of a partial cane is for illustrative purposes only and forms no part of the claimed design.

FIG. 1

FIG. 2
